UNITED STATES PATENT OFFICE

BERT BENSON WOOD, OF OAKLAND, CALIFORNIA

STEAM TURBINE

Application filed February 14, 1930. Serial No. 428,457.

This invention relates to improvements in turbines.

The primary object of this invention is the provision of an improved turbine, preferably using steam as the motive fluid, and which is very compact as to size, light in weight; and capable of producing great power at relatively high speeds.

A further object of this invention is the provision of an improved steam turbine which is relatively simple in construction, so far as number of parts is concerned, which has an improved baffle and blade construction arranged at the facing surfaces of the rotor and stator between which the propellant fluid is adapted to pass, by means of which the steam may exert its reactionary force constantly against the rotor over a relatively long course, and through a series of steps, for the efficient utilization of the same, in developing greater power and speed.

A further object of this invention is the provision of an improved steam turbine in which the expanding gas or steam enters between the cooperating faces of the rotor and stator at a location adjacent the axis of rotation of the rotor, and therefrom exerts its expanding and reactionary force upon the rotor over a multiple stepped arrangement of baffles during its passage radially outwardly with respect to the axis of rotation of the rotor.

Other objects and advantages of this invention will be apparent during the course of the following detailed description.

In the drawings, wherein for the purpose of illustration is shown only a preferred embodiment of the invention,

Figure 1 is a vertical sectional view taken through the turbine diametrically intersecting the shaft of the rotor.

Figure 2 is an inside view of an end wall of the turbine stator.

Figure 3 is an end view of the turbine, showing the base in section.

Figure 4 is a sectional view taken through the base of the turbine, looking upward in the direction of the turbine.

Figure 5 is an end view of one of the stator frusto-conical shaped parts, showing the

baffle arrangement at a face thereof, which cooperates with the rotor in receiving the motive fluid thereagainst, the view being arranged as an observer would see the parts looking axially along the turbine.

Figure 6 is a sector cut from the stator member of Figure 5, looking radially from the axis of the rotor in the direction of the baffle face of the part.

Figure 7 is a fragmentary perspective view, partly in section, showing the baffle arrangement at the stator part at a receiving face of the part of Figures 5 and 6.

Figure 8 is a view looking axially along the rotor, of one of the rotor operating parts, looking in the direction of the stepped baffle face thereof, against which the propellant fluid impinges, to cause rotation.

Figure 9 is a fragmentary view, partly in section, of the rotor part of Figure 8, looking radially at the same.

Figure 10 is a perspective view of a sector cut from the part of Figure 8, to better illustrate the stepped baffle means thereon.

Figure 11 is a sectional view longitudinally of the axis of the turbine from the inner face of one of the stator cones, showing in section the relative arrangement of baffles and blades of the rotor and stator.

Figures 12 and 13 are respectively views taken substantially on their respective lines 12-12 and 13-13 of Figure 1 of the drawings.

In the drawings, wherein a preferred embodiment of the invention is shown, the letter A may generally designate the turbine, which may include a stator B mounted upon a base C and having therein a rotor D operatively connected with a shaft E.

The stator B includes a cylindrical casing portion 15, to which a pair of effective stator parts 16 and 17 are internally connected; the parts 16 and 17 being each of hollow frusto-conical formation, with the smaller ends thereof in abutment against and connected with a narrow connecting and steam pressure cylinder 18 connected within the casing body 15, diametrically thereacross. At the larger end of the stator parts 16 and 17, the stator casing includes end walls 19 and 20, furnish-

ing bearings 21 therein for the proper support of the shaft E. The stator casing body 15 rests upon and is supported by the base C in a manner to be subsequently described.

Referring to the rotor D, the same consists of a pair of preferably hollow frusto-conical shaped parts 25 and 26, respectively cooperating in complementary turbine relation with the parts 16 and 17 of the stator B. These rotor parts 25 and 26 have the smaller ends thereof connected together and axially keyed with the shaft E.

Referring more specifically to the path of motive fluid, which is preferably high pressure steam, and its cooperation within the turbine, the cylindrical body portion 15 is provided with a radial connection 27 for the attachment of a suitable steam conduit or pipe therewith. The cylindrical portion 18 of the turbine comprises a pair of disc-shaped walls 29 and 30, which are spaced relatively close together, and provide therebetween a narrow ring-shaped compartment surrounding the shaft E concentrically, designated at 31, wherein the high pressure steam is admitted to the turbine from the connection 27. The walls 29 and 30 are connected at their outer peripheries by a cylindrical wall 32, integral with the walls 29 and 30, and outwardly flanged and riveted as at 33 to the cylindrical body 15 of the stator, in the position shown in Figure 1, in a medial plane between the stator and rotor parts 16-25 and 17-26. These walls 29 and 30 converge to restrict the compartment 31 in the vicinity of the shaft E, and are connected together by means of an annular web-like wall 38, having ports 39 therethrough for admission of steam from the chamber or chest compartment 31 into an annular chamber 40 surrounding the connecting hubs 41 and 42 of the rotor parts 25 and 26, from whence it passes along the stepped spaces between the rotor and stator parts 25-16 and 26-17, as will be subsequently detailed.

The rotor parts 25 and 26 are preferably independently formed and connected together in the vicinity of the shaft E and therefrom they relatively diverge outwardly from the shaft and about the shaft to provide an annular chamber in which the stator parts 16 and 17 nest. The rotor parts 25 and 26 are more specifically detailed in Figures 8, 9 and 10 of the drawings, wherein the rotor part 25 is more specifically detailed. It includes, as above mentioned, the hub portion 41. Each of the rotor parts 25 and 26 includes the outer tapered peripheral surface thereof, provided with a series of concentrically arranged relatively stepped annular shoulders 44, 45, and 46 of relatively increasing diameter from the hub portion outwardly, whereon the baffle structures, normally constituting the rotor turbine blade means, are disposed, in identical series. They

are of course arranged concentric with the axis of the shaft E. The arrangement of baffles on each of the shoulders 44, 45 and 46 is identical, consisting of a series of relatively spaced substantially J-shaped baffles 48, mounted at the outer margins of the stepped shoulders 44, 45 and 46, having the bights 49 recessed therein facing axially of the shaft in the direction of the adjacent cooperating baffle means on the stator part 16 or 17, as the case may be; this baffle means of the stator comprising diagonally positioned baffles 50, relatively spaced as shown in Figure 13, and to be subsequently described. The vertical riser shoulders adjacent the shoulders 44, 45 and 46 have associated therewith directly upon and preferably connected with the baffles 48 above described, a plurality of arcuated baffle blades 51, shown in Figure 12, and elsewhere in Figures 8, 9 and 10, the shaft facing edges of which terminate short of the tread shoulders 44, 45 and 46 respectively adjacent thereto, so that steam may pass through the spaces between the baffle blades 48, around the annular space 52 between the vertical riser surface 53 of the rotor and the baffles 48, through the spaces between the arcuated baffle blades 51 and into the spaces between the next outer series of diagonal baffles 50 of the stator, as shown in Figures 12 and 13, and in a relation which will appear more fully hereinafter. It is to be noted that an annular series of these arcuate baffles 51 is disposed on the vertical riser 60 of each of the rotor parts 25 and 26, immediately adjacent the hub of the respective rotor parts, and spaced at their inner peripheral edges from the hub to define the annular space 40 above mentioned, through which steam circulates as it enters the turbine.

The inner peripheral faces of the frusto-conical shaped stator parts 16 and 17 are of identical construction, and stepped in a complementary relation with the steps of the respective rotor parts 25 and 26, and provided with baffle means for cooperation therewith. Thus, each stator part 16 and 17 is provided with an innermost annular surface 61 adapted to immediately face the annular baffle arrangement of the respective rotor part whereon the baffles 51 are positioned at the riser shoulder 60. In annular offset and stepped concentric relation therewith are tread shoulders 63 and 64, spaced in parallelism and complementary spaced facing relation with the tread shoulders 44 and 45 of the respective rotor part. Outwardly thereof of the stator B is provided with an annular channel-shaped groove or compartment 66 immediately facing the shoulder 46 of the adjacent rotor part cooperating therewith, and as shown in Figure 1. The annular relatively stepped shoulders 61, 63 and 64 are each provided with series of the relatively

spaced diagonal baffles 50 thereon, which are inclined from their inner ends to their outer ends facing the adjacent blade means of the rotor, in the general direction of rotation of the rotor, and the spaces therebetween receive the expanding steam, entrapping it therein and causing it to expand in the direction of the adjacent blade means of the rotor parts, sending it into the spaces between and against the baffles 48, as shown in Figure 13, to cooperate in rotating the rotor parts.

It is thought that the operation of the invention will best be understood by reference to the cycle of the motive fluid. As before mentioned the high pressure steam enters the chamber 31 and passes into the annular space 40 about the exterior of the hubs 41 and 42 of the rotor, which are bolted together at 68, as seen in Figure 1. The steam entering this annular space 40 passes in both directions radially outwardly through the spaces between the baffles 51 of the rotor, which are connected on the riser portions 60 of the rotor parts immediately facing the same. The expanding steam acting on the inclined arcuated shoulders of these baffles 51, in the relation shown by the arrow in Figure 11 of the drawings, of course causes a rotary action of the rotor. It is to be noted that the riser surfaces of the rotor parts are beveled where they join the tread shoulders of the rotor parts, and the facing surfaces of the walls 76 to be subsequently mentioned are also beveled, as shown in Figure 1, so that the ports between the baffles 51 widen at their outer ends, to enable the steam to wedge its expanding pressure against the enlarged V-shaped shoulders of the baffles 51 of the rotor parts. Therefrom the expanding steam passes into the spaces between the inclined baffles 50 of the stator, upon the steps 61 of the stator parts 16 and 17, and the steam expanding in those spaces causes the same to outlet diagonally against the bight portions 49 through the spaces between the baffles 48 upon the shoulders 44 of the rotor parts, and which reaction impels the rotor, as can readily be understood. The steam therefrom passes into the annular spaces 52 surrounding the shoulders 44 to the rear of the baffles 48, as shown in Figure 13, and therefrom the expanding steam passes outwardly through the spaces between the arcuate baffles 51 adjacent the shoulders 44, and which steam reacting thereagainst as shown by the arrows in Figure 11, causes a further impelling of the rotor. The cycle of operation of the expanding motive fluid is repeated as it passes through the series of like baffle arrangements of the rotor and stator parts, with respect to the succession of steps 45 and 46. The expanding steam as it passes through the spaces between the outermost baffles 51 of the rotor parts 25 and 26, impinges, as shown in Figure 11, against the concave sides of arcuate baffles 70

which are carried in the channel-shaped space of the stator immediately facing the outermost shoulders 46 of the rotor parts. The steam passes between these baffles 70, and outwardly beyond this series of baffles 70, the stator parts 16 and 17 have an annular chamber, relatively large, into which the dead steam passes, and exists therefrom through exhaust ports 71 into the exhaust chambers 72 located at each side of the steam cylinder 18, between the latter and the adjacent surfaces of the stator parts 16 and 17, as can be understood from Figure 1 of the drawings. Therefrom the exhaust steam passes through suitable ports 73 in the lower portion of the body casing 15 of the turbine, and enters a chamber 74 of the base B, passing therefrom downwardly through an opening 75 adapted to receive a coupled connection of an exhaust conduit.

In addition to the features above described it is to be noted that imperforate wall portions 76 are rigid or integral with the baffles 48 and the inner edges of the baffles 51, preventing outlet of steam in that direction and insuring that the steam will pass through the ports between said baffles. Annular spring urged packing rings 80, which are retained in suitable slots 81 of the stator parts 16 and 17, as shown in Figure 1, are urged against the inner sides of the wall portions 76. It is to be noted that the walls 76 successively increase in diameter for the various stepped series of baffles between the rotor and stator parts, and that the innermost walls 76 do not obstruct the annular chamber or space 40 for passage of steam in the relation above described.

The casing of the turbine includes the disc-like end walls 19 and 20, as above described, each of which includes a hollow tapered hub portion 82, wherein the tapered bearings 21 adjustably seat. The shaft E of course extends through these bearings 21 and the inner ends of the hub portions 82 are provided with walls 83, against which compressible washers 84 seat, being urged into leak-proof connection with the adjacent shaft and housing parts. The bearings 21 are of any approved bearing material, and converge axially in the direction of the rotor hubs. At their outer ends another series of compressible washers 85 are disposed within the hubs 82 of the end plates of the rotor casing, and these washers are compressed and the bearings 21 adjusted by means of end caps 87 adjustably threaded into position in the ends of the hubs 82, and held in definite relation by set screws or other means 88.

With respect to the rotor hub facing ends of the bearing hubs 82, it is to be noted that the hubs 41 and 42 taper convergently in the direction of the bearing hubs 82, and at their outer ends seat into suitable tapered sockets 89 provided in the extreme inner ends of the

bearing hubs 82. The ends of the rotor hubs in the sockets bear against suitably ground washers 90 which are fitted to size to prevent end play of the shaft E and rotor within the stator housing, in a relation which will be apparent to those skilled in the art. Suitable oil ducts 92 permit lubricant to enter to the ground washers 90 from the stator housing.

It is to be noted that the bearings 21 are externally recessed and have oil ducts 94 leading to the spindle ends of the shaft E. Suitable lubricant means 95 is carried on each of the end walls 19 and 20 of the turbine casing, for admission of lubricant to the ducts 94, and suitable valve control grain conduits 97 may be employed therewith for draining of lubricant from the passageways about the bearings 21.

The end plate 19 is preferably provided with a detachable and adjustable cap 100, holding a suitable anti-friction bearing 101 therein, against which the ends of the shaft E bear, as shown in Figure 1. The opposite end of the shaft E may receive suitable means 102 for connection of a pulley or other apparatus thereto.

In order to provide an efficient connection of the parts, it is to be noted that the stator parts 16 and 17, in addition to being connected to the body casing 15 as above described, may have a screw threaded connection at 105 with the opposite walls of the steam cylinder or casing 18. It is furthermore to be noted that the outer peripheral edges of the rotor parts 25 and 26 have a rather close fitting joint connection at 107 with the inner facing peripheral edge at the outer large diameter portion of the stator parts 16 and 17 respectively, as shown in Figure 1. Suitable packing 108 may prevent loss of motive fluid, wherever desired.

In order to reinforce the end walls 19 and 20, the same may be provided with suitable reinforcing webs 110, and access to the chambers between the end walls of the casing to the internal parts of the turbine may be had through suitable openings 111, shown in Figure 2, which are normally closed by swivel man-hole covers 112, shown in Figure 3.

It is within the contemplation of this invention to provide any approved number or series of steps between the rotor and stator parts, for accommodating the baffles, as desired. Furthermore, it is to be noted that a preferred arrangement of the steps is that the inner steps will be narrower than the outermost steps; the steps successively increasing in width outwardly as the diameter of the steps increases. It is furthermore contemplated that the baffles 51 of the rotor parts 25 and 26, do not need to be of the height shown, but may be cut shorter to increase the radial height of the steam circulating passageways 52. It is also contemplated by me to utilize different means for

admission of the high pressure steam to the central portion of the rotor, if desired, and instead of using the stator and rotor parts in duplicate, as shown, I may use merely one rotor and one stator part in the broadest relation described. 70

The stator parts 16 and 17 are screw threaded at 20^a with the end plates 19 and 20.

Various changes in the shape, size, and arrangement of parts may be made to the form 75 of invention herein shown and described, without departing from the spirit of the invention or the scope of the claims.

I claim:

1. As an article of manufacture a steam engine stator comprising a plurality of relatively concentric steps each having a face thereof parallel to the axis of the concentric steps provided with a plurality of rigidly mounted diagonally sloping ribs defining diagonal steam expanding passageways therebetween, the stator at its outermost portion annularly beyond the step of greatest diameter being provided with a channel facing the axis of the concentric steps, said channel 90 having baffles therein arcuated with concave baffle faces facing said axis, said last mentioned baffles being relatively spaced and located at the entrance of said channel to provide an annular passageway in the channel 95 communicating with said spaces between the baffles, said stator having transverse ports to said channel passageway for exhaust of motive fluid.

2. As an article of manufacture a motive 100 fluid operated turbine rotor comprising a hub portion and having a series of relatively stepped concentric shoulders of successively increasing diameter concentric with the axis of the rotation of the rotor, said shoulders of the surfaces facing away from the axis of rotation of the rotor having baffles at the outermost marginal portions of the shoulders relatively spaced from each other and providing concave baffle edges facing in 110 the normal direction of a cooperating stator part, said baffles being spaced from the adjacent riser portions of the adjacent steps and defining annular passageways about the stepped shoulders therebehind, said baffles 115 being of less radial height than the height of the riser portions of said steps, and a series of inclined spaced baffles outwardly beyond the first mentioned baffles on each of said stepped portions, having inclined baffle surfaces facing the annular passageway above mentioned, the outermost ends of each series of baffles last mentioned terminating flush with the next outermost annular shoulder.

3. In a turbine the combination of a stationary casing, a shaft axially therein, stator and rotor parts operatively associated within the casing and with said shaft, the casing including end plates having tapered bearing passageways therein, adjustable tapered 130

bearings in said tapered passageways, said bearings having passageways therethrough for receiving the ends of the shaft, and means for adjusting said tapered bearings longitudinally in the tapered passageways.

4. In a turbine the combination of a stator casing, a shaft, a rotor keyed with the shaft including oppositely extending tapered hub extensions, end supporting plates on the stator casing having passageways therethrough for receiving the ends of the shaft, adjustable bearings in said passageways for directly receiving the ends of the shaft in bearing relation therein, and ground washers fixed in the plates surrounding the ends of the shaft and against which the hub portions of the rotor engage.

5. In a turbine the combination of a stator casing, a shaft, a rotor keyed with the shaft including oppositely extending tapered hub extensions, end supporting plates on the stator casing having passageways therethrough for receiving the ends of the shaft, adjustable bearings in said passageways for directly receiving the ends of the shaft in bearing relation therein, ground washers fixed in the plates surrounding the ends of the shaft and against which the hub portions of the rotor engage, and means for admission and drainage of lubricant with respect to the bearings of the ends of said shaft.

6. In a turbine the combination of a stator having a series of continuous circular concentric steps formed upon a face thereof, said steps having spaced baffles diagonally disposed thereon defining inclined channels therebetween, a rotor provided with a series of continuous circular concentric steps adapted to interfit in a complementary relation with the respective positioned steps of the stator, said rotor in the riser sides of the stepped portions facing axially of the rotor having steam admission ports which extend into the walls through the stepped portions of the rotor, said ports outletting upon the annular tread portions of said steps in facing proximity with the diagonal channel ways of the stator, said ports through the walls of the stepped portions of the rotor being shaped so that the expanding force of the motive fluid will impel the rotor about its axis, said rotor at each of the stepped portions thereof, at the juncture where the ports meet which outlet on the riser and tread portions of each of said steps, having a continuous circular chamber therein into which the expanding steam enters as it passes between said ports, and means for exhausting the motive fluid with respect to the stator and rotor parts.

BERT BENSON WOOD.
